APPARATUS FOR KNITTING

Brooke W. Lerch, Dundalk, and Clyde N. Stover, Towson, Md., assignors to Western Electric Company, Incorporated, New York, N. Y., a corporation of New York

Application February 7, 1940, Serial No. 317,648

9 Claims. (Cl. 66—9)

This invention relates to an apparatus for knitting and more particularly to an apparatus for forming a knitted covering on a conductor.

In applying knitted coverings to different types 5 of conductors, it is frequently desirable to change the closeness of the knitting or the amount of textile material applied for a given length of conductor without changing the speed ratios and other co-ordinated factors of the knitting 10 apparatus.

An object of the present invention is to provide a knitting apparatus wherein the closeness of knitting is independent of fixed characteristics 15 of the apparatus.

15 In accordance with one embodiment of the invention, a knitting machine is provided having a jack cylinder and needle cylinder having different numbers of slots with an offset connection between the jacks and needles.

20 A complete understanding of the invention may be had by reference to the following description taken in conjunction with the accompanying drawings, in which

Fig. 1 is a fragmentary vertical section of a 25 knitting head embodying the invention;

Fig. 2 is a schematic plan view of the needle head shown in Fig. 1;

Fig. 3 is a perspective detail view of a needle 30 jack and portion of a needle; and

Fig. 4 is a development of a knitted pattern made by the apparatus.

The apparatus to which this invention is applicable is disclosed more in detail in the copending application of S. E. Brillhart application

35 Serial No. 218,330, filed July 9, 1938, and only so much of the present apparatus is disclosed as is necessary for a full understanding of the invention.

40 Referring to Fig. 1, a rotatable jack cylinder 6 is shown having vertical slots 7 in its outer periphery in which needle jacks 8 and 9 are reciprocable. The needle jacks have butts 11 extending through slots 12 into the interior of the cylinder, and the needle jacks are held in place by a sleeve 13 which surrounds the cylinder and is held in place by a screw 14. The upper end of the cylinder carries a bearing support 15 in which the upper end of a hollow tubular shaft 16 is journaled in a ball bearing 17. Shaft 16 45 has a pair of collars 18 and 19 mounted thereon at an angle and a pair of cams 21 and 22 are journaled in ball bearings on the collars 18 and 19 respectively. The angles of the collars 18 or 50 19 are so disposed that the high points of the cams 21 and 22 are 180° apart. The outer

peripheries of the cams 21 and 22 are provided with projections or teeth which engage with similar projections or teeth on the needle jack butts to reciprocate the needle jacks. The upper end of the knitting head is provided with a 5 needle cylinder 25 having slots 26 therein in which the needles 27 may be reciprocated. The upper ends of the needle jacks are bifurcated and engage projections or butts 28 on the needles to reciprocate the needles. 10

In applying knitted coverings to different types of conductors it is frequently desirable to vary the closeness of the knitting or, in other words, to vary the number of wales for a given length of conductor. This varies the amount 15 of textile material applied to a given length of conductor. Referring, for instance, to Fig. 2, it will be seen that the jack cylinder 6 shown therein is provided with eighteen slots, and for one particular type of knitted covering it may 20 be desirable to use eighteen needles and seven stationary thread supplies arranged about the cylinder. If, then, the shaft 16 carrying the cams 21 and 22 is rotated four and one-half times as fast as the needle cylinder, a knitted 25 pattern of eighteen wales per revolution of the needle cylinder will be made. If, now, it is desired to make a less closely knit covering and provide only fourteen wales per revolution of the needle cylinder, four of the needles may be 30 omitted. The pattern made by thus omitting the needles, however, will be rough and non-uniform due to the unequal spacing of the needles. 35

A smooth and uniform pattern may be made by providing a needle cylinder 25 having fourteen uniformly spaced needle slots and providing needle jacks having an offset portion, as shown in Fig. 3. Referring to Fig. 2, for instance, a 40 jack cylinder 6 is shown having eighteen slots for needle jacks, and a needle cylinder 25 is shown having fourteen uniformly spaced slots. Needle jacks are omitted from the slots numbered 4, 8, 14 and 15, and the needle jacks are bent or shaped in such a way that the non-uniformly distributed needle jacks engage the uniformly spaced needles. In this arrangement the slots 5, 9, 13 and 17 are blank. Needles 1, 3, 6, 9 and 12 are actuated by the cam 21, and needles 2, 4, 5, 7, 8, 10, 11, 13 and 14 are actuated 45 by cam 22. Thus when the shaft 16 is rotated four and one-half times as fast as the knitting head, a pattern such as shown in Fig. 4 is made. In this pattern seven stationary thread supplies 50 are shown indicated by the numerals 1 to 7, 55

shown horizontally above the pattern, and the wales formed by needles 1 to 14 are shown vertically on the left side of the pattern. It will be evident from this that fourteen wales are 5 made for each revolution of the knitting head, whereas if eighteen needles were used, there would be eighteen wales per revolution of the cylinder and therefore a less closely knitted pattern using less textile material will result when 10 only fourteen needles are used.

It will be understood that the nature and embodiment of the invention herein described is merely illustrative and that many changes and modifications may be made therein without 15 departing from the spirit and scope of the invention.

What is claimed is:

1. In a knitting machine, a plurality of thread supplies, a needle cylinder, a plurality of needles 20 uniformly spaced circumferentially on said cylinder and reciprocable thereon, a jack cylinder, a plurality of jacks for actuating said needles non-uniformly spaced on said jack cylinder, means for rotating said cylinders, and means for 25 actuating said jacks in timed relation to the rotation of said cylinders to form a knitted fabric.

2. In a knitting machine, a needle cylinder, a needle reciprocable thereon, a jack cylinder, and 30 a jack for actuating said needle reciprocably mounted on the jack cylinder out of alignment with said needle, said jack having a circumferentially offset portion so as to engage the needle.

3. In a knitting machine, a needle bed having 35 evenly spaced needles mounted thereon, a jack bed having unevenly spaced jacks mounted thereon, said unevenly spaced jacks being shaped to engage said evenly spaced needles, and means for actuating said needles through said jacks to 40 form a knitted fabric.

4. In a knitting machine, a needle cylinder, a plurality of needles provided with butts, a jack cylinder, a plurality of jacks having means for 45 engaging the needle butts, said needles being uniformly spaced about the needle cylinder, said

jacks non-uniformly spaced, and means for actuating said jacks to form a knitted fabric.

5. In a knitting machine, a needle cylinder, a plurality of needles uniformly spaced mounted thereon, a jack cylinder having uniformly 5 spaced slots therein, the number of slots in the jack cylinder being greater than the number of needles, a plurality of jacks equal to the number of needles in said slots, and means for actuating the jacks to cause the needles to form a knitted 10 fabric.

6. In a knitting machine, a jack cylinder having a plurality of evenly spaced slots, a needle cylinder having a lesser number of slots, a needle reciprocable in each of said needle cylinder slots, 15 jacks reciprocable in as many slots in the jack cylinder as there are needles, said jacks being shaped to engage said needles, and means for actuating said jacks to cause the needles to form a symmetrical knitted fabric. 20

7. In a knitting machine, a needle cylinder having a plurality of needles, a pair of cam elements having their high points 180° apart, and a plurality of jacks engaging said needles at one end and at the other end engaging said cam 25 elements at unequally spaced points to cause the needles to knit a symmetrical fabric.

8. In a knitting machine, a plurality of knitting needles, a cam element and needle jacks interconnecting said cam element and needles, 30 some of said jacks having one end out of circumferential alignment with the other to engage the cam element at points to produce a symmetrical knitted fabric.

9. In a knitting machine, a plurality of evenly 35 spaced needles, a cam element for actuating a portion of said needles, a second cam element for actuating the remainder of said needles, and a plurality of jacks engaging said evenly spaced needles at one end and at the other end engaging 40 the cam elements at unevenly spaced points to form a symmetrical knitted fabric.
